UNITED STATES PATENT OFFICE.

CHARLES H. NIGGEMAN, OF LEXINGTON, MICHIGAN.

BUTTON OR STUD.

SPECIFICATION forming part of Letters Patent No. 281,642, dated July 17, 1883.

Application filed April 5, 1883. (No model.)

To all whom it may concern:

Be it known that I, CHARLES H. NIGGEMAN, of Lexington, in the county of Sanilac and State of Michigan, have invented certain new and useful Improvements in Buttons, Studs, and other like Fastenings, of which the following is a full, clear, and exact description.

This invention relates to separable buttons, under which term is designed to be included studs and other like fastenings having a double head, or head and base with connecting shank or stem, and made to engage with and disengage from one another, subject to the control of a spring.

My invention has for its objects the construction of a superior stud or button of this description, which shall work easier, be safer as regards accidental detachment, durable, cheap, simple, and easily repaired.

Reference is to be had to the accompanying drawings, forming part of this specification, in which similar letters of reference indicate corresponding parts in all the figures.

Figure 1 represents a longitudinal view, upon an enlarged scale, of my improved stud or button. Fig. 2 is a longitudinal section of the same on the line *xx* in Fig. 1. Fig. 3 is an inner face view of the separated base of the button with attached tube and spring, and Fig. 4 an inner face view of the separated head of the button with attached post or stem and catch.

A in the drawings is the base of the stud or button, having a central tube, *b*, mounted on its inner face, and a spiral or other spring, *c*, secured at its one end to said face within the tube, the tension of said spring being in direction of the length of the tube. An outwardly protruding hollow circular bead or groove, *d*, is made in and around said tube, near its outer end, and connecting with this circular groove, and extending to the outer end of the tube, are opposite outwardly or laterally protruding grooves or grooved ways *e e*. Furthermore, said tube is constructed on opposite sides of its outer end portion, midway between the longitudinal grooves *e e*, with outside short longitudinal slots, *ff*, made to terminate at their inner ends in and cutting the circumferential hollow bead or groove *d*.

B is the separable top or head of the button. This head is provided on its inner face with a centrally-projecting post or stem, *g*, of a suitable length to enter down within the

tube *b* and compress the spring *c* therein, and at a suitable distance in the length of said post are opposite side catches or projections, *h h*, which are here shown as formed by a pin passing transversely through the post. These catches *h h* are of a size to freely enter the longitudinal grooves *e e* in the tube *b*.

To fit the two parts A B of the stud or button together, the post *g* of the head B is adjusted to bring its catches *h h* in line with or over the longitudinal grooves *e e* of the tube *b*, and said post passed down within said tube till the catches enter within or strike the bottom of the circular groove *d*, compressing the spring *c* in the tube. The head B is then turned the fourth of a circle, or thereabout, to bring its catches *h h* in line with the slots *ff* in the tube, and pressure removed from the head B, when the spring *c*, acting against the post *g*, forces outward said post till the catches *h h* are arrested by the outer ends of the slots *ff*, and the head and base of the stud or button are securely locked with each other.

To separate the head B from the base A, the head is pressed down to bring the catches *h h* within the circular groove *d*, and then turned to bring said catches in line with the longitudinal grooves *e e*, when the spring *c* will assist in forcing the head away from the base, and its post readily passes out of the tube *b* of the base.

While it is preferable to provide duplicate catches *h*, grooves *e*, and slots *ff*, as described, the separable stud or button may only have one of each of these, if desired, without changing the general principle or action.

I am aware that it is not new to use a base carrying a slotted tube, a spring in the tube, and a button having a side pin on its shank; but

What I do claim as new and of my invention is—

The base-tube *b*, having the hollow circular head *d* and slots *ff*, said head arranged horizontally about the tube, and provided with the vertically and diametrically opposite ways *e e*, in combination with the button-shank *g*, having the cross-pin *h*, projecting on opposite sides, as shown and described.

CHARLES HENRY NIGGEMAN.
